UNITED STATES PATENT OFFICE.

GEORGE W. BLANKENHORN, OF SAN FRANCISCO, CALIFORNIA, ASSIGNOR, BY DIRECT AND MESNE ASSIGNMENTS, TO CALIFORNIA PACKING CORPORATION, OF SAN FRANCISCO, CALIFORNIA, A CORPORATION OF NEW YORK.

ROLLING CUTTER.

1,407,316.

Specification of Letters Patent. Patented Feb. 21, 1922.

Application filed August 28, 1916. Serial No. 117,188.

To all whom it may concern:

Be it known that I, GEORGE W. BLANKENHORN, a citizen of the United States, residing at the city and county of San Francisco and State of California, have invented new and useful Improvements in Rolling Cutters, of which the following is a specification.

This invention relates to a paper lining machine.

10 One of the objects of the present invention is to provide a machine for cutting blanks or irregular shapes from sheet material, such as paper, rubber, and the like, and especially a simple compact machine 15 for cutting circular paper gaskets or washers, and inserting them into can ends or other receptacles.

Further objects will hereinafter appear.

The invention consists of the parts and 20 the construction and combination of parts as hereinafter more fully described and claimed, having reference to the accompanying drawings in which:—

Figure 1 is an end view of the machine 25 partly broken away.

Figure 2 is a side elevation partly in section showing one of the side frames A removed.

Figure 3 is a longitudinal section of the 30 can end feeding device.

Figure 4 is a perspective view of a can end.

Figure 5 is a perspective view of a paper 35 gasket cut by the circular dies shown on the present machine.

Figure 6 is a plan view of the die for cutting oval shaped gaskets.

Figure 7 is a plan view of a die for cutting rectangular shaped gaskets.

40 Referring to the drawings in detail, A indicates a frame in which is secured a bearing shaft 2 supporting a tubular driving shaft 3, and a rotary die wheel 4.

Mounted in guide ways 5 formed in the 45 frame is a pair of slidable bearing blocks 6, and journaled in said bearing blocks is a rotary platen member 7. Interposed between the bearing blocks 6 and a pair of plates 8, is a pair of tension springs 9, one for each 50 end of the platen, which is provided for the purpose of forcing the platen with sufficient pressure against the dies generally indicated at B to sever the stock 10 which is fed between

the platen and the dies as will hereinafter be described. Suitably secured in the face 55 of the wheel 4 are the dies B. These dies are each provided with an annular groove for the reception of a knock-out ring 11, and the outer and inner edges such as indicated at 12 and 13 are beveled off to form the cutting 60 edges of the dies.

Extending through the body of each die is a pair of pins 14, the inner ends of which are secured to the knock-out ring while the free ends are secured to the head or plate 65 15 between which and the die are interposed tension springs or coil springs 16 which normally maintain the knock-out rings in the retracted position shown at 17 in Figure 2.

Mounted interior of the annular inner 70 cutting edge 13 formed on each die, or in the depression formed by the inner beveled edge, is a knock-out head 18. This head is provided for the purpose of ejecting the central blanks left when the cutting operation takes 75 place, this being automatically performed by the function of a spring 19 housed in the body of the die and engageable with a collar 20 formed on the stem 21.

Mounted adjacent each die are two pairs 80 of can end centering arms generally indicated at 22 and 23. Each pair of arms is pivotally mounted as at 24 on a pin 25, which in turn is pivotally mounted in a projecting lug formed on the face of the die wheel. 85 The inner end of each arm rests on the outer beveled face of the cutting edge 12, and means have been provided for raising and lowering each set of centering arms with relation to the cutting edge 12, as will hereinafter be described. Connecting the inner 90 ends of each set of arms is a coil spring 26 and connecting each set of arms with a depressible plunger 27 is a cross head 28 which projects through slots 29 formed in the 95 arms.

The present die wheel shown is provided with four cutting dies such as indicated at B, four bearing lugs 25^a and two pairs of centering arms for each die and each pair 100 of centering arms is provided with a plunger 27 as shown, there being eight in all. Secured on the stationary bearing shaft 2 interior of the die wheel 4 is a cam 30. This cam is mounted in alignment with heads 31 105 formed on the plungers, and these will there-

fore be depressed by the cam in successive order as the die wheel revolves continuously with uniform speed in the direction of arrow *a*. Each pair of centering arms is in 5 this manner raised or projected with relation to the annular cutting edge 12, the moment a cooperating plunger 27 engages the cam and this position is maintained until the plunger moves out of engagement with 10 the cam at the point indicated at 32. The plunger with each pair of connected centering arms, is here retracted, and the centering arms depressed with relation to the cutting edge by means of coil springs 33.

15 By referring to Figures 1 and 2 it will be seen that each pair of centering arms is pivotally mounted as at 24 upon a pin 25 which in turn is pivotally mounted in the bearing lug, the arms when projected will therefore 20 cause the pin 25 to turn in its bearing and the pivotal mounting 24 of each arm will at the same time permit the coil spring 26 to pull the arms together until they engage with the inner ends of the cross head 28 25 which forms a stop to limit this movement. A reverse action takes place when a plunger moves out of engagement with the cam at the point indicated at 32 as the surrounding coil spring 33 will retract the plunger and 30 connected centering arms, the pin 25 will then turn in opposite direction in the bearing lug and the centering arms will spread as they are forced down over the inclined annular flaring face of the die, finally assuming 35 the spread depressed position shown at 36. (See Fig. 1.) The die wheel 4 is provided with four spokes such as indicated at 37 and each spoke is provided with a forked lever 38 which is pivotally mounted in the 40 spoke as at 39. The forked end of the lever engages a cooperating plate 15, while the outer end of each lever is adapted to be raised or lowered during the rotation of the die wheel by a stationary cam 40 as will 45 hereinafter be described.

Formed on the exterior face of the die wheel is a pair of cam tracks 41 and 42. These tracks are positioned one on each side of the dies, and are provided for the purpose 50 of supporting the rotary platen 7 during the rotation of the die wheel when a die is in register with the platen. Each cam track is recessed as at 43 at points in alignment with a die, and mounted adjacent said recessed 55 portions in each cam track, is a pair of pivotally mounted adjustable cams 44. Each individual cam is raised or lowered by means of a set screw 45 passing through the rim of the die wheel, and therefore permits each individual cam to be raised or lowered with relation to the cutting edge of the adjacent die, 60 in this manner permitting the rotary platen when leaving the cam tracks 41 and 42, to engage the cutting edge of the die with as 65 little shock as possible, and similarly to leave

the cutting edge of the die and engage the cam track without unnecessarily elevating or disturbing the position of the platen.

Journalized in a pair of extension arms formed on the main supporting frame A is a 70 pair of feed rollers 46 and 47. The paper from which the gaskets are cut is delivered from a roller or any other means of supply, as a continuous strip 48 to the feeding rollers shown and is fed by said rollers to a point 75 where the paper will assume a position intermediate of or between a set of cutting dies and the rotary platen. The lower feed roller is an idler and is preferably constructed of rubber while the upper feed roller is continuously driven from the main driving shaft 3 by means of chain, gears, or any other suitable form of mechanism which ensures a uniform drive between the main feeding roller 46 and the die wheel 4. While 80 the die wheel rotates continuously with a constant speed, it is necessary that the paper be intermittently fed, as considerable waste would otherwise take place. This is accomplished by providing a raised portion 49 on 85 the driving roller, and as this engages the paper and the lower roller, sufficient pressure is brought to bear to feed the paper in a forward direction between the cutting dies and the cooperating platen. The paper strip will 90 however remain stationary the moment the raised portion has been turned sufficiently far to relieve the paper of pressure on the lower roller. This takes place at the time when a die leaves the platen, and the paper 95 will therefore remain stationary during the time period of rotation, while the succeeding die is moving into place. The raised portion will then engage the lower feeding roller and feed the paper forward with the incoming 100 die. The pressure of the tension springs 9 on the platen 7 is sufficient to sever the interposed sheet and force it into the annular groove formed for the reception of the cut gasket. It will here remain until the knock-out ring 11 is depressed, as will hereinafter 105 be described, while the central blank formed while the gasket is being cut, is automatically knocked-out by the head 18, the moment the die moves out of engagement with 110 the platen.

Any means not here shown may be provided for removing the center blanks from the machine.

Journalized in a pair of extension arms on 115 the main supporting frame opposite the arms which support the feeding rollers 46 and 47, is a roller 50. This roller is preferably constructed of a soft rubber or fabric, and is provided for the purpose of forcing the 120 cut gasket further into the annular recess formed between the cutting edges of the dies, thereby preventing the cut gasket from accidentally falling off before it is positively 125 knocked out by the ring 11. The roller 50 130

is stationary and stands in a position where each passing die will exert sufficient pressure upon it to cause the surface of the roller to force itself into the annular groove 5 in the die. The paper gasket is in this manner prevented from falling out or becoming accidentally mis-placed before the proper time for its removal is reached.

Mounted on one side of the revolving die 10 wheel is a curved guide chute 51, to which the can ends such as indicated at 52 are delivered in any suitable manner. One form of mechanism such as shown in Figure 3 has however been successfully employed. This 15 device consists of an angularly disposed chute or hopper 53 to which the can ends are delivered by means of a conveyor belt or other suitable means not here shown. The can ends entering this chute are stacked 20 one on top of the other, and they are discharged one by one into the curved chute 51 at timed intervals to deliver one can end to each die as they move into register with the chute. The release or removal of each 25 individual can end from the chute or hopper 53 is accomplished by the following mechanism:—

Journalized under the base 54 of the hopper 53 is a pair of sprocket wheels 55 and 56 30 on which is mounted an endless chain 57. Suitably secured on the chain is a plurality of fingers 58 which are so positioned as to project through a slot formed in the base 54 in this manner engaging the lowermost 35 can end and forcing it in a forward direction to a point where it is delivered to the chute 51. The sprocket wheels 55 and 56 are timed and driven directly from the main driving shaft 3, and the spacing of the projecting lugs 58 is such that a can end will 40 be delivered to the chute 51 every time a die has moved into register with the chute, or assumed the position shown at 60 in Figure 2.

The operation of the device as a whole will 45 be as follows:—

With power transmitted to the die wheel 4 it can readily be seen that the continuous 50 rotary movement of this wheel will bring one die after another into engagement with the platen 7. The interposed paper sheet 10 delivered thereto by the feeding rollers 46 and 47 is in this manner severed, or a gasket such as shown in Figure 5 formed. This gasket is forced into the annular 55 groove of the die just above the knock-out ring 11, and is forced further into said annular groove when the die moves into engagement with the roller 50 as previously described. The cycle of operation of an individual die will be as follows:—

After the paper has been cut and forced 60 into the annular groove by the platen 7 and the roller 50, it will be seen that the die will move into register with the chute 51. The 65 lowermost pair of centering arms 23 will,

when this position is assumed, be projected as the cooperating plunger 28 has already moved into engagement with the cam 30. The can end feeding device as shown in Fig. 3 driven in unison with the die wheel, 70 will at the same time deliver a can end to the chute, and as the centering arms 23 have been projected, it can be seen that this will form a stop to prevent further movement of the can end 52. The continuous rotary 75 movement of the die wheel will however permit the can end to move down through the chute in unison with the die. The second pair of centering arms 22 will next be projected by its cooperating plunger 28 as this 80 moves into engagement with the cam, in this manner engaging the opposite edge of the can end, thus positively gripping it and centering it with relation to the die and the annular groove. The can end positively 85 gripped and centered with relation to the die, continues its movement through the chute until the forked lever 39 engages the cam 40 and depresses the disc 15 with connected knock-out ring 17. This causes the 90 paper gasket to be ejected and forced into the annular groove 80 of the can end. A further movement of the die will bring the first 95 plunger 28 to the point 32 where it leaves the cam 30. The interposed coil spring will thus retract the plunger and connected centering arms 23 thus freeing one side of the can end at the point where the curve chute 51 connects with a discharging chute 64. The second pair of centering arms 22 are 100 maintained in their raised position until the cooperating plunger reaches the point 32 of the cam, they thus act as pushers to push the can end out of the curved chute into the discharging chute 64 which conveys the can 105 end to any desirable point.

From the foregoing description it will be seen that the paper gaskets are not only cut, but that they are placed also in can ends before a complete revolution of an individual 110 die has taken place. The centering arms provided are of great importance as they serve the function of centering the can ends with relation to the individual dies, and positively feed same until the discharging 115 point is reached; the gasket being ejected from the die and placed in the can end during the passage of the can end through the curved chute. Everything in connection with the present machine is automatic and 120 requires no attention once the proper adjustments have been made. The continuous rotary movement employed permits the machine to operate with considerable speed, and as all intermittent motions and reciprocating parts are reduced to a minimum, it can readily be seen that wear and tear is reduced to a minimum.

The provision of the cam tracks 41 and 42 together with the adjusting cams 44, pro- 125

vides a simple means for raising and lowering the platen with relation to the individual dies, in this manner saving the cutting edges, and furthermore permitting the cutting of gaskets of practically any shape desired.

The oval and rectangular cutting dies shown in Figures 6 and 7 may be substituted for the circular dies shown in the present machine without changing any part of the mechanism now employed. These irregular shaped gaskets are cut just as easily as a circular gasket, and the efficiency and general output of the machine will be the same in either direction. While four cutting dies are here shown as arranged upon the periphery of the die wheel, it is obvious that any number may be employed, and that the speed of rotation may be such as conditions and requirements may demand.

The cylindrical shaped platen 7 employed is not positively driven, but will be revolved by frictional engagement with the contacting dies and cam tracks. The dies proper are preferably made of a high grade steel, while the platen 7 is made of some softer material such as soft steel, brass, fibre, fabric, rubber, or the like.

The materials and finish of the several parts of the machine may otherwise be such as the experience and judgment of the manufacturer may dictate.

I wish it understood that various changes in form, proportions, and minor details of construction may be resorted to within the scope of the appended claims, and that I do not wish to limit myself to the specific design or construction here shown.

Having thus described my invention, what I claim and desire to secure by Letters Patent is:—

1. In a paper lining machine, a continuously moving die adapted to cut and receive a paper gasket, means for delivering and centering a can end with relation to the die and means for transferring the gasket directly from the die into the can end while the die is moving.

2. In a paper lining machine, a rotor, a plurality of cutting dies carried thereby, all presenting flat cutting faces, an annular channel formed in each die, a platen engageable with each die, a yieldable mounting for the platen, means for feeding a paper sheet between the platen and the dies, means for exerting a pressure on the platen to permit the cutting edges of each die, when passing over the platen, to cut a paper gasket and simultaneously to permit the platen to force said gasket into the channels formed in the dies for the reception of the gaskets, means for delivering a can end to each die and means for transferring the gasket to the ends.

3. In a paper lining machine, a rotor, a

platen mounted adjacent the rotor, a plurality of die members carried by the rotor and successively engageable with the platen, means for feeding stock to be cut between the platen and each individual die, means for retaining the cut stock in each individual die during a portion of the revolution of the rotor, means for delivering a can end to each die, means on each die for centering the ends, other means for exerting pressure on the ends to hold the same in snug engagement with the dies, and means for transferring the cut stock from the dies to the ends.

4. In a paper lining machine for can ends, a continuously moving die member adapted to cut, receive and carry a paper gasket, means for delivering a can end to the die, means for centering the end with relation to the gasket in the die, and means for transferring the gasket from the die directly to the end.

5. A paper lining machine comprising a frame, a die wheel journaled in the frame, a cylindrical platen adjacent the die wheel, a pair of floating bearing members mounted in the frame supporting the platen, a plurality of interspaced cutting dies secured in the face of the die wheel, track members formed on the said wheel on each side and between two adjacent dies, means for exerting pressure on the platen to maintain it in engagement with the track members and dies, a pair of annular cutting edges and an intermediate channel formed on each die, means for feeding a paper sheet between the die wheel and the platen to permit the cutting edges of each individual die when engaging with the platen to cut a paper gasket and simultaneously to permit the platen to force said gasket into the channel of the engaging die, and a secondary mechanism for forcing the cut gasket further into the channel.

6. A paper lining machine comprising a frame, a die wheel journaled in the frame, a cylindrical platen adjacent the die wheel, a pair of floating bearing members mounted in the frame supporting the platen, a plurality of interspaced cutting dies secured in the face of the die wheel, track members formed on the said wheel on each side and between two adjacent dies, means for exerting pressure on the platen to maintain it in engagement with the track members and dies, a pair of annular cutting edges and an intermediate channel formed on each die, means for feeding a paper sheet between the die wheel and the platen to permit the cutting edges of each individual die when engaging with the platen to force said gasket into the channel of the engaging die, means for delivering can ends to a point adjacent the die wheel, means for engaging and centering a can end with relation to each die,

and means for ejecting the paper gasket and forcing it into the can end during said period of engagement.

7. A paper lining machine comprising a frame, a die wheel journaled in the frame, a cylindrical platen adjacent the die wheel, a pair of floating bearing members mounted in the frame supporting the platen, a plurality of interspaced cutting dies secured in the face of the die wheel, track members formed on the said wheel on each side and between two adjacent dies, means for exerting pressure on the platen to maintain it in engagement with the track members and dies, a pair of annular cutting edges and an intermediate channel formed on each die, means for feeding a paper sheet between the die wheel and the platen to permit the cutting edges of each individual die when engaged with the platen to force said gasket into the channel of the engaging die, means for delivering can ends to a point adjacent the die wheel, means for engaging and centering a can end with relation to each die, and means for ejecting the paper gasket and forcing it into the can end during said period of engagement.

8. In a paper lining machine, a rotor, a cylindrical platen mounted adjacent the rotor, a plurality of die members on the rotor successively engageable with the platen, a pair of continuous cutting edges and an intermediate channel formed in each die, means for feeding a paper sheet between the platen and the dies, means for exerting pressure on the platen to permit the cutting edges of each die when engaging with the platen to cut a paper gasket and simultaneously to permit the platen to force said gasket into the channel of the die, means for delivering can ends to a point adjacent the rotor, means for engaging, securing and centering a can end with relation to each die, and means for ejecting the paper gasket and forcing it into the can end during said period of engagement.

9. In a paper lining machine, a rotor, a cylindrical platen mounted adjacent the rotor, a plurality of die members adjacent the rotor successively engageable with the platen, a pair of continuous cutting edges and an intermediate channel formed in each die, means for feeding a paper sheet between the platen and the dies, means for exerting pressure on the platen to cut a paper gasket and simultaneously to permit the platen to force said gasket into the channel of the die, means for delivering can ends to a point adjacent the rotor, means for engaging, securing and centering a can end with relation to each die, and means for ejecting the paper gasket and forcing it into the can end during said period of engagement.

10. The combination with a continuously revolving rotor having a plurality of re-

cessed cutting dies secured around its periphery, of a cylindrical platen mounted adjacent the rotor and engageable with the dies, means for feeding a paper sheet between the platen and the dies to permit the dies to cut the paper against the platen and simultaneously to permit the platen to force the cut paper into the die recesses, means for successively delivering can ends to a point adjacent the rotor, means cooperating with each individual die for engaging, centering and securing, each can end delivered with relation to each die, and means for transferring the cut paper from the dies to the can ends during said period of engagement.

11. The combination with a continuously revolving rotor having a plurality of cutting dies secured around its periphery, of a cylindrical platen mounted adjacent the rotor and engageable with the dies, means for feeding a paper sheet between the platen and the dies to permit the dies to cut the paper against the platen and simultaneously to permit the platen to force the cut paper into a recess formed between the cutting edges of the dies, means for successively delivering can ends to a point adjacent the rotor, means cooperating with each individual die for engaging, centering and securing each can end delivered with relation to each die, means for transferring the cut paper from the dies to the can ends during said period of engagement.

12. A unitary machine for cutting and inserting sealing gaskets in can ends comprising a continuously moving cutting means, means for feeding paper thereto, receiving means in the cutting means for securing the gaskets cut, and means for feeding can ends to the receiving means.

13. In a paper lining machine for can ends, a continuously moving die member adapted to cut, receive and carry a paper gasket, means for delivering the can end to the die, means on the die for centering the end with relation to the gasket in the die, and means for transferring the gasket from the die to the end.

14. In a paper lining machine for can ends, a die wheel, a plurality of straight-faced cutting dies carried by the wheel, a yieldably mounted plate member under which the dies are adapted to pass in successive order, means for passing the material to be cut between the platen and the dies, and means on each die for receiving the material cut, means interposed between each die for supporting the yieldably mounted platen member, means for delivering can ends in successive order one to each die, means for causing each can end to travel in unison with its die and means for transferring the cut material from the dies to the can ends during their travel with the dies.

15. In a paper lining machine for can ends, a continuously moving die member having straight-faced circular continuous cutting edges all positioned on a common 5 plane, said die adapted to travel in a circular path, a yieldingly mounted platen member under which the die is adapted to pass, means for feeding the material to be cut between the platen and the die, means 10 on the die for receiving the material cut, and means for transferring the material from the receiving means to a can end.
16. In a paper lining machine, a continuously revolving rotor having a plurality of 15 cutting dies arranged around its periphery, means for feeding paper thereto to be cut into gaskets, means in each cutting die for receiving the gaskets, a can end feeding device cooperating with the rotor and the dies 20 adapted to deliver can ends in successive order to each die, means for centering the ends with relation to each die, a curved chute mounted on one side of the rotor adapted to engage the ends and maintain 25 them in snug engagement with the respective dies, and means for transferring the gaskets from the dies to the can ends while they are in engagement with the curved chute.
17. In a paper lining machine for can 30 ends, the combination of a continuously traveling die member, a roller platen engageable with the die member in the course of travel of the latter, means for feeding material between the platen and the die to cut 35 a gasket and force it into the die, and mechanism for transferring the cut gasket from the die member to a can end during the travel of the die member and while the die is in motion.
18. In a continuously operating lining 40 apparatus for can ends, the combination of a continuously moving means including a die for cutting and receiving a can end liner, means for delivering a can end into 45 receiving position with respect to the die and causing the can end to travel for a limited period in unison with the die, and means for transferring the can end liner from the die into the can end.
19. In a continuously operating lining 50 apparatus for can ends, the combination of a continuously moving means including a die for cutting and receiving a can end liner, means for delivering a can end into 55 receiving position with respect to the die and causing the can end to travel for a limited period in unison with the die, means for transferring the can end liner from the die into the can end, said last-named means 60 carried by and movable with the die.
20. In a paper lining machine a rotor, means carried by said rotor for receiving paper gaskets, means for delivering can 65 ends to said receiving means, means on the receiving means for engaging and center-
- ing the can end with relation thereto, a curved chute engaging the end and holding the same in snug engagement with the receiving means, and automatic actuated means for transferring the gaskets from the receiving means to the can ends during movement of the rotor.
21. A unitary machine for cutting and inserting sealing gaskets in can ends comprising a continuously moving cutting 75 means, means for feeding paper thereto, receiving means in the cutting means for securing the gasket cut, means for feeding can ends to the receiving means, and means for transferring the gaskets from the receiving means to the can ends.
22. A unitary machine for cutting and inserting sealing gaskets in can ends comprising a continuously moving cutting 80 means, means for feeding paper thereto, receiving means in the cutting means for securing the gasket cut, means for feeding can ends to the receiving means, means for transferring the gaskets from the receiving means to the can ends, and means for dis- 85 charging the can ends after the gaskets 90 have been inserted.
23. In a paper lining machine, a continuously revolving rotor, a plurality of interspaced cutting dies carried by the rotor, 95 a pair of continuous cutting edges and an intermediate continuous channel in each die, means for feeding paper to the dies, a platen member cooperating with the dies to cut gaskets from the paper and to force 100 said gaskets into the channels, means for delivering a can end to each die, means for positively engaging each can end to permit it to travel with the rotor during a portion 105 of its revolution, and means for transferring the gaskets to the can ends during said traveling period.
24. In a paper lining machine, a continuously revolving rotor, a plurality of interspaced cutting dies carried by the rotor, 110 a pair of continuous cutting edges and an intermediate continuous channel in each die, means for feeding paper to the dies, a platen member cooperating with the dies to cut gaskets from the paper and to force 115 said gaskets into the channels, means for delivering a can end to each die, means for positively engaging each can end to permit it to travel with the rotor during a portion of its revolution, means for transferring the gaskets to 120 the can ends during said traveling period.
25. In a paper lining machine, a continuously revolving rotor, a plurality of interspaced cutting dies carried by the rotor, a pair of continuous cutting edges and an 125 intermediate continuous channel in each die, means for feeding paper to the dies, a platen member cooperating with the dies to cut gaskets from the paper and to force 130 said gaskets into the channels, means for de-

- livering a can end to each die, means for positively engaging each can end to permit it to travel with the rotor during a portion of its revolution, a knock-out member 5 mounted in each die channel, and means for automatically depressing each knock-out member to transfer the gasket to the can ends during said traveling period.
26. In a continuously operating can end 10 lining machine consisting of a rotary support, a die member thereon cooperating with a platen member for cutting a ring liner, the die member constructed and arranged to receive and carry the liner, means for delivering can ends into receiving position in 15 juxtaposition with the die member after the ring liner is cut and received, and means for transferring the liner to the can end whilst the die is traveling.
- 20 27. In a can end lining machine, the combination of a rotary carrier, a die member mounted thereon, the face of said die member lying entirely in the plane of a cord of the arc of the circumference of said carrier, 25 a platen having radial movement with respect to said carrier, and engageable with the surface of the die member during the travel of the latter, means for feeding paper between the platen and the die member, 30 means for delivering a can end to the die member, means on the die member for centering the can end with relation to the die and means for transferring the cut material from the die to the end.
- 35 28. In a paper lining machine, a continuously moving cutting die adapted to cut and receive a paper gasket, means for delivering a can end to the die, means for centering the end with relation to the gasket 40 in the die, means for forcing the can end against the die, and means for ejecting the gasket from the die and inserting it directly in an annular channel formed in the can end.
- 45 29. In a machine for applying ring liners to can ends, the combination of a continuously traveling die member, associated mechanism for cutting and receiving a liner into the die member, means for delivering 50 can ends singly to the die member, and means for transferring the liner from the die member into the can end.
30. In a paper lining machine, a rotor, a plurality of channeled dies on the rotor for cutting and receiving paper gaskets, an annular ejector ring in each die, a plurality of pins secured to each ring and slidably mounted in each die, a central plate on each die and secured to the adjacent pins, and a stationary cam member engageable with each plate during rotation of the rotor.
31. In a paper lining machine, a rotor, a plurality of channeled dies on the rotor for cutting and receiving paper gaskets, an ejector in each die, and a stationary cam member adjacent the rotor adapted to impart a reciprocal movement to each ejector as the dies move into a predetermined position, and means for placing a can end in front of each die and centering it with relation thereto a moment previous to the time that the ejectors are reciprocated.
32. In a paper lining machine, a movable die adapted to cut and receive a paper gasket, means for delivering a can end to said die, means for centering the end with relation to the gasket in the die, and an inclined chute adjacent the die for forcing the end snugly against the die.
33. In a paper lining machine, a movable die adapted to cut and receive a paper gasket, means for delivering a can end to said die, means for centering the end with relation to the gasket in the die, and a guide adapted to engage the can end and gradually force and hold the end snugly against the die.
34. In a machine for applying ring liners to can ends, a continuously revolving die wheel, a plurality of dies carried thereby, a frame in which the die wheel is supported, a stationary shaft extending through said frame, a sleeve shaft passing through one of the frames and journaled therein, said sleeve shaft supporting the die wheel, a cam member within the die wheel supported by the stationary shaft, an annular recess formed in each die, a knock-out ring in each recess and means for transmitting a reciprocal movement to each knock-out ring when passing over the stationary cam.
- In testimony whereof I have hereunto set my hand in the presence of two subscribing witnesses.

GEORGE W. BLANKENHORN.

Witnesses:

JOHN H. HERRING,
W. W. HEALEY.
